UNITED STATES PATENT OFFICE.

JOHN ROTHERAM, OF CREIGHTON, AND ALBERT E. EVANS, OF PITTSBURGH, PENNSYLVANIA, ASSIGNORS TO PITTSBURGH PLATE GLASS COMPANY, A CORPORATION OF PENNSYLVANIA.

GLASS-TANK CONSTRUCTION.

Application filed July 20, 1926. Serial No. 123,628.

The invention relates to a tank or furnace construction and particularly to that employed at the outlet end of a tank from which glass is continuously withdrawn in the form of a sheet or ribbon. The invention has for one of its primary objects the provision of an arrangement which will add to the safety of the tank. A further object is the provision of improved means for supporting the outlet slot member and for positioning it with exactness to bring the slot at the proper level. A still further object is the provision of improved means for preventing the slot member from being bent or sprung outwardly intermediate its ends under the pressure of the head of molten glass in the tank. One embodiment of the invention is illustrated in the accompanying drawings, wherein:

Figure 1 is a vertical section through the apparatus. Fig. 2 is a horizontal section on the line II—II of Fig. 1. Fig. 3 is a partial front elevation and partial vertical section on the line III—III of Fig. 1. Figs. 4 and 5 are detail views of the supporting beams for the outlet member, Fig. 4 being a front elevation and Fig. 5 a plan view. Figs. 6, 7 and 8 are detail views of the pressing device for the lower beam of the outlet member, Fig. 6 being a plan view, Fig. 7 being a section on the line VII—VII of Fig. 6, and Fig. 8 being a section on the line VIII—VIII of Fig. 6. And Figs. 9, 10, and 11 are detail views of one of the arch or roof members, Fig. 9 being a plan view, Fig. 10 a longitudinal section, and Fig. 11 a transverse section on the line XI—XI of Fig. 10.

Referring to the general arrangement of Figs. 1, 2 and 3, 1 is the forward end of a glass melting tank and 2 is the forehearth of such tank, from which molten glass is delivered between the sizing rolls 3 and 4 and thence over the apron 5 and into a leer, the rolls and apron being supported upon a truck 6 carried by the wheels 7. The roof of the forehearth is made up of the movable members 8 and 9 between which is mounted the gate 10. This gate is provided with suitable overhead lifting means, not shown, and when lowered serves to cut off the flow of glass to the sizing rolls 3 and 4. When in the position shown, this gate closes the space between the roof members 8 and 9, so that it is always ready for service, but if desired, the gate may be removed, and the opening closed by a third roof member similar in construction to the roof members 8 and 9.

The walls of the tank and forehearth are preferably supported by vertical I-beams 11, 12, 13, 14, 15, 16 and 17, as indicated in Fig. 2, such vertical I-beams also serving as supports for other parts, as hereinafter set forth. Extending transversely of the front wall of the tank at the lower portion thereof, are the three beams 18, 19 and 20, which beams engage the vertical bars 21 resting against the clay work of the furnace. The beams are preferably made up of channels, as indicated in Fig. 1, the lower beam 20 being supported from the foundation channel 22 by means of posts 23 arranged at suitable intervals along the length of the beams. The ends of the beams 18, 19 and 20 are provided with the caps 24, and these caps are secured to the I-beams 15 by means of the turnbuckles 25 (Fig. 2). The beams are preferably made hollow and provided with suitable connections 26, 27, whereby a cooling fluid, such as water, may be circulated through the beams. This adds a large degree of safety to the apparatus, as it sometimes happens that a flow of glass escapes through the slot member 28 and down the front wall of the tank, or the slot may give way, and the heat from this mass of glass is sufficient to soften the metal supporting beams, unless protected in some way. The failure of these beams, and the consequent failure of support to the clay work at the front side of the tank might result in the accidental emptying of the tank and involve great loss and damage.

The slot member 28 is of clay and provided with the outlet opening 29 through which a flow of glass to the sizing rolls 3 and 4 occurs. This slot member is supported at its lower edges by the transverse metal beams 30 and 31 having the flanges 32 and 33 extending over the vertical face of the clay work a substantial distance in order to give a firm support to the clay work against outward movement. These beams are preferably in the form of hollow castings of great strength and rigidity and are provided with connections 34 and 35 (Figs. 4 and 5) whereby a flow of cooling fluid, such

as air or water, may be directed through the members, and thus protect them from weakening incident to the application of a high degree of heat. This provision for cooling 5 adds to the safety of the slot member for the reason heretofore explained in connection with the beams 18, 19 and 20, this applying particularly to the lower beam 31. The ends of the beams 30 and 31 are extended, as indicated in Figs. 4 and 5, and the beams tied together at such ends by the vertical bolts 36, 36 so that on tightening these bolts, the clay member 28 is clamped therebetween. Other clamping means for the sides of the 10 clay member are also provided in the form of the plates 37 and 38, which are moved inward by means of the screws 39. In order to clamp the slot member tightly against the front wall of the forehearth, the tie rods 15 40 are employed, such tie rods extending through the perforations 41 in the ends of the beam members and being secured at their other ends to the vertical I beams 14. Additional security is afforded by the clamping 20 means 42 (Fig. 2) which engage the beams 12 and pass around the rods 40. Additional support for the vertical corner portions 43 of the forehearth walls is also provided by the diagonal connecting rods 44 25 (Fig. 2), which are hooked around the vertical bolts 36 at their inner ends (Fig. 3) and at their other ends extend through brackets 45 riveted or welded to the vertical I-beams 11. The connecting rods 44 in connection with the beams 30 and 31, thus provide horizontal tie rods extending from the vertical I-beams 11 on one side of the forehearth to corresponding beams on the other side, thus adding a substantial degree of 30 strength to the framework supporting the forehearth. In order to prevent the beam 31 from sagging, bolts 46 are employed (Figs. 1 and 4), which extend through the walls of the beam 31 and engage the beam 18 35 lying therebeneath. These bolts are threaded through nuts 47 seated in recesses in the lower wall of the beam 31 and by turning the heads of the bolts they may be brought down into engagement with the beam 18 and provide the necessary support.

In order to brace the beam 31 against forward deflection, the central supporting bar 48 is employed, such support being shown in Figs. 1, 6, 7 and 8. This bar is 40 mounted for sliding movement in the top of the truck 6 and may be moved inward by means of the bell crank lever 49, pivoted at 50 to a bracket 51 secured to the truck body and operated by the connecting rod 52. This connecting rod extends through a U-shaped bracket 53 at the rear end of the truck, and is engaged by a nut 54, such nut having a flange 55 lying beneath the perforated strip 56 so that a swivel support 45 is provided for the nut and it is held against

movement in either direction. By rotating the nut, the bell crank lever 49 is swung so that the forward member of the rod 48 presses tightly against the beam 31, and thus tends to prevent any deflection outward of 70 the central portion of this beam.

The roof or arch members 8 and 9, which lie to the rear of the slot member 28 are preferably constructed as shown in Figs. 9, 10, and 11. Each member consists of a frame 75 made up of the channels 57, 57 placed back to back and secured together by means of the bolts 58. This beam or frame is provided at its ends with the downwardly projecting brackets 59, 59, such brackets preferably being in the form of steel castings riveted or bolted to the channels 57, 57. Each bracket carries four bolts 60 working through the nuts 61 mounted in suitable recesses in the castings. The inner ends of 80 these bolts engage the inclined face plates 62. Clamping plates are thus provided which can be moved in and out and tilted to any desired angle. Mounted between the face plates 62 are the refractory blocks 63, all slightly tapering so that the width at the lower ends is less than at the upper ends, giving them a wedge form. When the face plates 62 are moved in by the clamping 85 screws 60, so that they engage the faces of the end blocks and clamp them, an arch is provided giving very secure support to the series of blocks. The ends of the beam, when in use, rest upon the side walls of the 90 forehearth, as indicated in Fig. 3. The brackets 65 carried by the beams are perforated and provide a means whereby the beams may be engaged from an overhead crane and moved to and from position. A 95 movable roof for the forehearth is thus provided, which gives a secure support to the refractory blocks and reduces to a minimum the danger of a failure of the clay work at 100 this point.

What we claim is:

1. The combination with a tank adapted to carry a bath of molten glass, and rolling means at one side thereof for forming a sheet or ribbon of glass, of a clay outlet member intermediate the glass bath and the rolling 105 means provided with an outlet slot for conducting the glass to the rolling means, a hollow metal beam for supporting said member along one side and means for circulating a cooling fluid through such beam.

2. The combination with a tank adapted to carry a bath of molten glass, and rolling means at one side thereof for forming a sheet or ribbon of glass, of a clay outlet member intermediate the glass bath and the rolling 110 means provided with an outlet slot for conducting the glass to the rolling means, a pair of hollow metal beams extending along 115 the upper and lower edges of the outlet member and adapted to support such mem-

ber, and means for circulating a cooling fluid through said beams.

3. The combination with a tank adapted to carry a bath of molten glass, and rolling means at one side thereof for forming a sheet or ribbon of glass, of a clay outlet member intermediate the glass bath and the rolling means provided with an outlet slot for conducting the glass to the rolling means,

10 a hollow metal beam extending transversely of the tank below said outlet member and adapted to support the clay wall of the tank, and means for circulating a cooling fluid through said beam.

15 4. The combination with a tank adapted to carry a bath of molten glass, and rolling means at one side thereof for forming a sheet or ribbon of glass, of a clay outlet member intermediate the glass bath and the rolling means provided with an outlet slot for conducting the glass to the rolling means, a pair of hollow metal beams extending along the upper and lower edges of the outlet member and adapted to support such member, vertical tie members between the ends of the beams, and means for circulating a cooling fluid through the beams.

20 5. The combination with a tank adapted to carry a bath of molten glass, and rolling means at one side thereof for forming a sheet or ribbon of glass, of a clay outlet member intermediate the glass bath and the rolling means provided with an outlet slot for conducting the glass to the rolling means, a metal beam extending along the lower edge of said outlet member arranged

25 to support said edge and hold it against outward movement, and a brace extending transversely of the rolls therebeneath and engaging said beam intermediate its ends and supporting it against outward movement.

30 6. The combination with a tank adapted to carry a bath of molten glass, and rolling means at one side thereof for forming a sheet or ribbon of glass, of a clay outlet member intermediate the glass bath and the rolling means provided with an outlet slot for conducting the glass to the rolling means, a metal beam extending along the lower edge of said outlet member arranged to support said edge and hold it against outward movement, a brace extending transversely of the rolls therebeneath and engaging the central portion of the beam and means for adjusting the brace to cause it to exert pressure against the beam.

35 7. The combination with a tank adapted to carry a bath of molten glass, rolling means at one side thereof for forming a sheet or ribbon of glass, a truck on which the rolling means is seated, of a clay outlet member intermediate the glass bath and the rolling means provided with an outlet slot for conducting the glass to the rolling means,

means, a metal beam extending along the lower edge of said outlet member arranged to support said outlet member and hold it against outward movement, a brace for the beam carried by the truck and engaging the beam intermediate its ends, and means for causing the brace to exert a pressure against the beam.

40 8. The combination with a tank adapted to carry a bath of molten glass, and rolling means at one side thereof for forming a sheet or ribbon of glass, of a clay outlet member intermediate the glass bath and the rolling means provided with an outlet slot for conducting the glass to the rolling means, a pair of hollow metal beams extending along the upper and lower edges of the outlet member and adapted to support such member, vertical tie members between the ends of the beams, and means for circulating a cooling fluid through the beams.

45 9. The combination with a tank adapted to carry a bath of molten glass, and rolling means at one side thereof for forming a sheet or ribbon of glass, of a clay outlet member intermediate the glass bath and the rolling means provided with an outlet slot for conducting the glass to the rolling means, a pair of beams extending along the upper and lower edges of the outlet member with their ends protruding out past such member, vertical tie members between said ends, and other tie members secured to said ends and extending rearwardly along the sides of the tank for clamping the outlet member against the front end of the tank.

50 10. The combination with a tank adapted to carry a bath of molten glass, and rolling means at one side thereof for forming a sheet or ribbon of glass, of a clay outlet member intermediate the glass bath and the rolling means provided with an outlet slot for conducting the glass to the rolling means, a pair of beams extending along the upper and lower edges of the outlet member with their ends protruding out past such member, vertical tie members between said ends, other tie members secured to said ends and extending rearwardly along the side of the tank for clamping the outlet member against the front wall of the tank, vertical supporting beams at the ends of said front wall, and diagonal connecting rods securing the ends of said pair of beams to such vertical supporting beams.

55 11. In combination with a tank adapted to carry a bath of molten glass and having a drawing extension or forehearth at its front end of less height than the body of the tank, and rolling means at one side for forming a sheet or ribbon of glass, of a removable clay outlet member intermediate the end of the forehearth and the rolling means provided with an outlet slot, and constituting the upper portion of the front wall of the

forehearth, and a removable roof member for the forehearth to the rear of said outlet member extending transversely of the forehearth, and comprising a metal frame with 5 downwardly projecting inclined end members, and a set of wedge shape refractory blocks fitting against the lower side of the frame and supported therein by reason of their wedge shape and the engagement of 10 the end blocks with said inclined end members.

12. In combination with a tank adapted to carry a bath of molten glass and having a drawing extension or forehearth at its 15 front end of less height than the body of the tank, and rolling means at one side for forming a sheet or ribbon of glass, of a removable clay outlet member intermediate the end of the forehearth and the rolling means provided 20 with an outlet slot, and constituting the upper portion of the front wall of the forehearth, and a removable roof member for the forehearth to the rear of said outlet member extending transversely of the forehearth, and comprising a metal frame with 25 downwardly projecting inclined end members, and a set of wedge shape refractory blocks fitting against the lower side of the frame and supported therein by reason of their wedge shape and the engagement of the end blocks with said inclined end members, said end members having movable face plates and clamping means for moving them inward.

30 13. In combination with a tank adapted to carry a bath of molten glass and having a drawing extension or forehearth at its front end of less height than the body of the tank, and rolling means at one side for forming a sheet or ribbon of glass, of a removable clay 35 outlet member intermediate the end of the forehearth and the rolling means provided with an outlet slot, and constituting the upper portion of the front wall of the forehearth, and a removable roof member for the forehearth to the rear of said outlet member extending transversely of the forehearth, and comprising a metal frame with 40 downwardly projecting inclined end members, and a set of wedge shape refractory blocks fitting against the lower side of the frame and supported therein by reason of their wedge shape and the engagement of the end blocks with said inclined end members, said end members having movable face plates and clamping means for moving them inward and tilting them.

45 14. In combination with a tank adapted to carry a bath of molten glass and having a drawing extension or forehearth at its front end of less height than the body of the tank, and rolling means at one side for forming a sheet or ribbon of glass, of a removable clay outlet member intermediate the end of the forehearth and the rolling means provided 50 with an outlet slot, and constituting the upper portion of the front wall of the forehearth, and a removable roof member for the forehearth to the rear of said outlet member extending transversely of the forehearth, and comprising a metal frame with downwardly projecting inclined end members, and a set of wedge shape refractory blocks fitting against the lower side of the frame and supported therein by reason of their wedge shape and the engagement of the end blocks with said inclined end members, said end members having movable face plates and clamping means for moving them inward.

55 15. In combination with a tank adapted to carry a bath of molten glass and having a drawing extension or forehearth at its front end of less height than the body of the tank, and rolling means at one side for 60 forming a sheet or ribbon of glass, of a removable clay outlet member intermediate the end of the forehearth and the rolling means provided with an outlet slot, and constituting the upper portion of the front wall of the forehearth, and a removable roof member for the forehearth to the rear of said outlet member extending transversely of the forehearth, and comprising a metal frame with 65 downwardly projecting inclined end members, and a set of wedge shape refractory blocks fitting against the lower side of the frame and supported therein by reason of their wedge shape and the engagement of the end blocks with said inclined end members, said end members having movable face plates and clamping means for moving them inward.

70 75 80 85 90 95 100 In testimony whereof, we have hereunto subscribed our names.

JOHN ROTHERAM.
ALBERT E. EVANS.
